Inventor:

Fred A. Laraway
by *John G. Foster* Atty.

UNITED STATES PATENT OFFICE.

FRED A. LARAWAY, OF CLEVELAND, NEW YORK.

PACKING-HOLDER.

1,311,450.

Specification of Letters Patent. Patented July 29, 1919.

Application filed May 21, 1919. Serial No. 298,712.

To all whom it may concern:

Be it known that I, FRED A. LARAWAY, a citizen of the United States, residing at Cleveland, in the county of Oswego and 5 State of New York, have invented certain new and Useful Improvements in Packing-Holders, of which the following is a specification.

As is well known, it is the custom for 10 supply houses, garages, repair stations and the like to maintain supplies of repair parts of automobiles, including packing. This packing is ordinarily placed in boxes, drawers, and the like, and consequently not only 15 becomes crumpled and misshapen, but it is more or less difficult of access, and the amount on hand is not readily ascertainable.

It is the primary object of the present 20 invention to provide means for mounting the packing elements so that they are maintained in proper condition, each section or element being readily accessible and obtainable without disturbing any other, and the amount of stock on hand can be determined 25 with the greatest ease.

A further object is to provide as an article 30 of manufacture a holder with predetermined sets of packing thereon, which can be sold as an entirety and is in effect a display card for the material.

An embodiment of the invention that has 35 proven entirely practical and satisfactory is disclosed in the accompanying drawings, wherein:—

Figure 1 is a plan view of the same, Fig. 2 is a sectional view on the line 2—2 of Fig. 1.

Similar reference numerals designate 40 corresponding parts in all the figures of the drawings.

In the embodiment disclosed, a base plate 3 is employed which may be of wood or other suitable material, and is provided at one end with an opening 4 by which it may be hung 45 upon a wall. This plate is provided with outer sets of outstanding pins 5 and 6 that are spaced apart and so related that they will correspond to the usual bolt-receiving openings formed in packing strips. Thus 50 angular packing strips 7 are shown having standard bolt-receiving openings 8 in which

the pins 5 are engaged. Similarly, curved strips 9 are mounted on the lower sets of pins 6. These sets of pins are arranged along the margins of the base plate. Within 55 the same are other sets of pins 10, 11, 12 and 13 arranged to hold standard packing strips 14, 15, 16 and 17. The spaces still remaining may be occupied by packing washers 18 mounted on suitably arranged pins 19, and 60 sheets of packing 20 also employed in certain automobile engines, can be mounted upon a pin 21. It will be obvious that these packing elements are all maintained in their proper form and are all exposed to view. 65 Each is accessible and the number in stock can be quickly ascertained. In addition the arrangement is such that they occupy a relatively small amount of space. It will be evident that the holder can be manufactured, 70 and the packing applied thereto by the purchaser, or that a predetermined number of packings can be mounted thereon and the entire outfit sold as an article of commerce.

From the foregoing, it is thought that the 75 construction, operation and many advantages of the herein described invention will be apparent to those skilled in the art, without further description, and it will be understood that various changes in the size, shape, 80 proportion and minor details of construction may be resorted to without departing from the spirit or sacrificing any of the advantages of the invention.

Having thus fully described my invention, 85 what I claim as new, and desire to secure by Letters Patent, is:—

In an article of the character set forth, the combination with a base plate, of sets of packing holding pins projecting therefrom, 90 said pins being spaced apart and disposed in a relation to each other that corresponds to the standard bolt holes in the packing to be held and being furthermore adapted to engage in such bolt holes of such packing 95 and maintain the packing in proper shape.

In testimony whereof I affix my signature in the presence of two witnesses.

FRED A. LARAWAY.
